United States Patent Office.

WILLIAM C. GOODWIN, OF HAMDEN, CONNECTICUT.

Letters Patent No. 72,018, dated December 10, 1867.

IMPROVEMENT IN HAND-CULTIVATORS.

The Schedule referred to in these Letters Patent and making part of the same.

TO ALL WHOM IT MAY CONCERN:

Be it known that I, WILLIAM C. GOODWIN, of the town of Hamden, in the county of New Haven, and State of Connecticut, have invented a new and useful Improvement in Hand-Cultivators; and I do hereby declare that the following is a full, clear, and exact description of the construction, character, and operation of the same, reference being had to the accompanying drawings, which make part of this specification, in which—

Figure 1 is a perspective view of the cultivator complete and ready for use.

Figure 2 is a perspective view of one of the cultivator-blades, attached to the shank, upper side down, showing the guide or keel on the under side of the foot of the stock, to which the blade is attached.

Figure 3 is a perspective view of one of the blades when attached to the under side of the foot of the stock, showing the guiding shape of the stock.

Figure 4 is a plan of the frame C, to which I attach the shanks or stocks of the cultivator-blades.

My improvement consists in attaching the frame C, which holds the cultivator-blades, to the main frame G, (to which I attach the wheel and handle,) by means of two hooks or journals fitting into eyes or holes, (like hook-and-eye hinges,) and one binding-screw, with its head or cap; and in the method of adjusting the depth of the running of the blades, by means of two set-screws and the before-mentioned binding-screw; and in the construction and operation of the feet of the stocks, to which the blades are attached, that is, with the guide or keel on the bottom or sole of each foot, (like a skate;) and in the manner of attaching the handle to the main frame, and adjusting it to the proper height for the person using it.

I make the traction-wheel A of cast iron, or any other suitable material, with a broad tread or web, B, so that it may roll smoothly over the surface of the ground, and with an axis, terminating in two journals, which work in suitable bearings at the ends of the two bars *a* and *b* of the frame G, as indicated at *c*, all as represented in fig. 1.

I make the main frame G, (to which I attach the wheel A and frame C,) of cast iron, or any other suitable material, of two bars or shafts, as *a* and *b*, with a broad cross-bar, *d*, to connect them; and to the front end of each of the bars *a* and *b* I attach a suitable bearing for the journal of the axis of the wheel A; and near the front part of the cross-bar *d* I cast or fit two ears with holes in them, to serve as eyes to receive the hooks or journal *e* and *e'*, fig. 4, of the frame C, one of which ears is shown at *e*; and in the central part of the rear edge I cast or cut a space to receive the head of the binding-screw *f*, as represented at *g*, all as shown in fig. 1; and on the centre of the cross-bar *d* I cast or fit a tongue, as *h*, to which I attach a handle, D, by means of a joint-pin, *i*, making it adjustable vertically by means of the set-screw *j*, which works in a vertical slot in the tongue *h* to adjust it to the height of the person using it.

I make the frame to which I attach the cultivator-blades, of cast iron, or any other suitable material, substantially in the shape or form shown at C, fig. 1, and in plan in fig. 4. On the front edge of this frame C, I cast or fit two hooks or journals, as shown in plan at *e* and *e'*, fig. 4, to pass into the eyes or holes in the ears of the bar *d*, as indicated at *e*, fig. 1, in the same way as hook-and-eye hinges are put together; and near the rear edge I cast or cut slots, as *k l C m*, for the upper ends of the shanks, as in fig. 2. When I use three blades, as *n o p*, I generally use the slots *k* and *m*, and when I use two-blades, the slots *l* and *C*, in each of which slots I can adjust the stocks *q* and *r* of the blades *n* and *p* as to extreme width of cut or space between the rows; and when I use three blades, or only one, I use the one in the centre, as shown at *s t*, fig. 1.

I make the shanks or stocks *q t r* of malleable cast iron, or any other suitable material; and, to give the greatest degree of strength with the least weight, I make them broad and thin, and bring them essentially to an edge in front, as indicated at *u*, fig. 2, and *w*, fig. 3, so that they will pass freely through the ground; and on the bottom of the foot I form a guide or keel, as represented at *v*, fig. 2, which will prevent the cultivator from being thrown out of its course by small obstructions; and it also tends to strengthen the heel of the stock; and, if thought best for any reason, the blade may be attached to the under side of the foot, as shown in fig. 3, when the broad part of stock, at *w*, will steady the blade, as well as strengthen the shank or stock.

I cast or shape the upper end of the shank or stock so that it will move freely in the slots *k l C m*, and cut a thread on the extreme end, as shown at *u'*, fig. 2, to receive a nut, as shown near *k*, *s*, and *m*, fig. 1, by means of which I secure the shanks or stocks to the frame C.

I make the blades, of steel, or any other suitable material, substantially of the shape shown at *p*, figs. 1 and 2, and secure them to the feet of the stocks by rivets or any other convenient means.

I attach the frame *C* to the main frame *G* by passing the hooks or journals *e* and *e'*, fig. 4, of the frame *C* into the eyes or holes in the ears of the bar *d*, as indicated at *e*, fig. 1, that is, in the same manner that hook-and-eye hinges are put together; and I secure the frame in position by passing the head of the binding-screw *f* into the space *g* in the bar *d*, and binding it there by turning up the nut *z* until the set-screws *x* and *y* bear firmly against the outer corners of the bar *d*, all as shown in fig. 1.

To graduate the depth to which the blades will run under the surface, I insert two set-screws, as shown at *x* and *y*, (the positions of which are indicated in plan at *x* and *y*, fig. 4,) which, (being tapped into the frame *C*), *f* turned down, and the nut *z* turned up, the rear edge of the frame *C* will be elevated, and the points of the blades *n o p* will be depressed, and *vice versa*.

Having made the several parts, and connected and adjusted them as before described, I take hold of the cross-bar *E* of the handle *D*, and push the whole apparatus forward between the rows, when the wheel *A* will roll over the surface of the ground, and the blades will pass into the ground to the extent desired, when they will assume a horizontal position parallel with the level of the bottom of the wheel, or any other guide which may be used.

If found more convenient, the handle *D* may be made double or forked, or two separate handles may be used; and, if any one should desire to draw the apparatus by the handle instead of pushing it, the blades with their shanks may be reversed in the slots; and, if found more convenient at any time, the cultivator may be drawn by a horse, either with or without additional shafts.

What I claim as my invention, and desire to secure by Letters Patent, is—

1. The combination of the frame *C* with frame *G*, and the set-screws *x* and *y*, and binding-screw *f*, when they are constructed, arranged, and fitted for adjusting the blades, substantially as herein described and set forth.
2. The combination of the blade with the foot and shank, when the foot is made with a keel, like *v*, to guide the blade and strengthen the shank, substantially as herein described and set forth.
3. The combination of the handle *D* with the frame *G*, when the handle is made adjustable by means of the tongue *h* and set-screw *j*, and the whole is constructed, combined, and fitted for use substantially as herein described and set forth.

W. C. GOODWIN.
